UNITED STATES PATENT OFFICE.

JAMES F. McELROY, OF ALBANY, NEW YORK; SUSIE HALE McELROY, EXECUTRIX OF
SAID JAMES F. McELROY, DECEASED, ASSIGNOR TO CONSOLIDATED CAR-HEATING
COMPANY, A CORPORATION OF WEST VIRGINIA.

STEAM-TRAP.

1,145,910.

Specification of Letters Patent. Patented July 13, 1915.

Application filed January 12, 1912. Serial No. 870,899.

To all whom it may concern:

Be it known that I, JAMES F. McELROY, a citizen of the United States, residing at Albany, county of Albany, State of New York, have invented certain new and useful Improvements in Steam-Traps, the following being a full, clear, and exact disclosure of the one form of my invention which I at present deem preferable.

For a detailed description of the present form of my invention, reference may be had to the following specification and to the accompanying drawings, which illustrate my invention.

Figure 1 is a vertical central section on line 1—1 of Fig. 4 of my device; Fig. 2 is an external side elevation thereof; Fig. 3 is a plan view, and Fig. 4 is a horizontal section on the line 4—4 of Fig. 2.

My invention relates to a steam trap wherein the control-valve of the radiator is operated through a flexible wall intermediate between two chambers in the trap-casing.

Some of the features herein shown and described form the subject matter of a separate application of even date herewith and the features peculiar to my present invention comprise chiefly a trap-thermostat having double chambers and a device for securing straight-line action of the control valve.

Referring to Figs. 1 and 2 of the drawing, the trap-casing is composed of four sections A, B, C and D separated from one another on horizontal lines a , b , c . The section B is the trunk-section which contains the several inlet and outlet ports by which the apparatus communicates with the system in which it is placed. Section A is a cup-section covering the valve chamber, secured by bolts a^1 , a^2 , a^3 , a^4 , section C is a depending section, and secured by bolts b^1 , b^2 , b^3 , containing the spring and operating rod, and also serving to support section D, which is a basket-section containing the thermostat. The sections A, C and D are all secured to and supported by the trunk-section B. The steam from the source of supply, which is the train-pipe in a car-heating system for which my device is particularly adapted, enters through port X into a chamber W, formed in the trunk-section, and containing

a removable screen R that is held in position by a hollow screw-plug S³ containing the blow-off plug S². From chamber W the steam is admitted by the control valve into valve-chamber U whence it goes by port Y and pipe z to the radiator. The steam or water of condensation from the radiator flows through pipe z and port Z to chamber V whence it falls upon the thermostat in basket-section D. Chambers U and V are separated by a yielding or flexible wall composed of a corrugated cylinder F projecting into chamber U and closed at its upper end by a disk G¹ on the end of operating rod G. The corrugated cylinder is mounted on a bonnet E that is screwed into the rigid partition between the two chambers, the joint being made tight by suitable packing. A portion e^1 of bonnet E extends up into cylinder F and contains vertical slots in which travel the guide wings g on rod G, which protect the corrugated cylinder by preventing any attempt to turn the rod G attached thereto which would tend to break the brazed connection between disk G¹ and the cylinder. The space between the cylinder F and extension e^1 is drained by ducts e^3 which open into the space between rod G and bonnet E where it passes through the latter. The bonnet E extends beyond the line b which separates sections B and C, and is squared at its lower end to receive a wrench. By this means the bonnet can be screwed into or out of its seated position whenever the two sections are separated from each other. A spring N is seated at its upper end on bonnet E and at its lower end presses on spider G² on rod G, the spider serving as a guide for the rod and also permitting the water of condensation to pass down upon the thermostat.

So far as described my apparatus is the same as that appearing in my application aforesaid.

The thermostat of my present invention is formed of two hollow casings H¹, H², known as "diaphragms" which are adapted to contain alcohol or other liquid which vaporizes at a given temperature and thereby causes the containing diaphragm to expand and operate the control-valve of the radiator. By employing two diaphragms working in

series I am enabled to get a longer range of play with a less distortion of the diaphragm. The lower one is seated on the bottom of basket-section with a central bearing and the upper one is centrally seated on the upper one by an intervening central plate which carries a thin flexible web or disk h with lugs h^1 above and below it to support the outer or peripheral portions of the diaphragms. Ribs h^2 on the interior of the basket-section serve to hold the diaphragms centrally in the basket and guide them as they expand and contract vertically. On the center of the upper diaphragm H^2 bears loosely a downward extension G^3 from spider G^2 whereby the upward pressure of the expanding diaphragms is transmitted to rod G and thence to the control-valve, as will be hereinafter described. It will be observed that the line of contact between the upper diaphragm H^2 and extension G^3 is not far removed from the line of separation c between casing-sections C and D , so that by dropping one side of the basket-section around one of the hinge-bolts d^1 , d^2 which secure it to section C , the diaphragms can separate from extension G^3 and thus be easily removed from the basket, or conversely, can be placed in position with equal facility.

Turning now to the control-valve heretofore mentioned as located between chambers W and U , it is shown in Fig. 1 at P , being provided with a tubular valve-seat P^1 in which moves a guide-block p screwed to the under side of the valve and serving to guide it while still permitting the desired flow of steam through the valve-seat. The valve itself is secured to the lower end of a vertical rod P^2 which, at its upper end, moves in a guide-socket in the wall of cup-section A . A horizontal lever T with rounded end engages, on one side, with the rod P^2 and, on the other side, with a block G^4 adjustably connected to disk G^1 on the end of rod G , which disk also forms the closed upper end of the flexible cylinder F . By this arrangement a straight-line movement is communicated to the valve by the straight-line movement of rod G caused by the upward expansion of the thermostat or the downward pressure of spring N when the thermostat contracts.

What I claim as new and desire to secure by Letters Patent is:

1. A steam-trap comprising a casing having a valve-chamber and a thermostat-chamber communicating respectively with the opposite ends of the radiator, means for preventing direct communication between said chambers, a valve in said valve chamber, a plurality of separable hollow expansion diaphragms loosely mounted in series in the said thermostat-chamber and guided by the chamber walls, a separable spacer independently centered between the succeeding diaphragms,

and operating connections between the end diaphragm and the valve in said valve-chamber.

2. A steam-trap comprising a casing having a valve-chamber and a thermostat-chamber communicating respectively with the opposite ends of a radiator, means for preventing direct communication between said chambers, a valve in said valve chamber, a plurality of hollow expansion diaphragms mounted in series in the thermostat-chamber and independently centered and guided therein, a separable spacer independently centered between the succeeding diaphragms and operating connections between the end diaphragm and the valve in the valve chamber.

3. A steam trap comprising a casing provided with two chambers, a flexible wall separating the chambers, a valve in one chamber provided with straight line guides, a lever connection between the flexible wall and the valve, a rod for operating the flexible wall and two thermostats arranged in superimposed relation for operating the rod, the peripheries of said thermostats being separated by flexible bearing means.

4. A steam trap comprising a casing provided with two chambers, a flexible wall separating the chambers, a valve in one chamber, a jointed lever connection between the valve and the flexible wall, a rod for operating the flexible wall, two thermostats mounted in series in the casing for operating the rod, and a central support interposed between the thermostats and provided with a flexible web having lugs engaging the peripheral portions of said thermostats.

5. In a steam trap the combination with a casing having a basket, and a valve in said casing, of an operating thermostat for said valve comprising two unattached hollow diaphragms arranged in series with an intervening spacing device between them having both a central and a peripheral bearing on both diaphragms, the said thermostat being loosely contained in the basket portion of the trap and guided peripherally thereby.

6. In a steam trap the combination with a casing having a basket, and a valve in said casing, of an operating thermostat therefor comprising two unattached hollow diaphragms arranged in series, with an intervening spacing device flexible between its central and peripheral bearings, the said thermostat being loosely contained in the basket portion of the trap and guided peripherally thereby.

7. In a steam trap, the combination with a casing containing a valve chamber and a thermostat-chamber the two chambers being separated by a partition including a corrugated cylinder closed at its upper end and opening downwardly into the thermostat-chamber, of a thermostat in the thermostat-chamber comprising two separable dia-

phragms arranged in series, an operating rod interposed between said cylinder and the upper one of said diaphragms, a spring acting downwardly on said rod, and an operating connection in the valve-chamber between said cylinder and the valve.

5 In witness whereof I have hereunto set

my hand, before two subscribing witnesses, this tenth day of January, 1912.

JAMES F. McELROY.
